(57) CLAIM

The ornamental design for a paper roll holder as shown and described.

DESCRIPTION

FIG. 1 is a perspective view of a paper roll holder showing my new design;

FIG. 2 is another perspective view thereof in an environment of use;

FIG. 3 is a front elevational view thereof;

FIG. 4 is a top plan view thereof;

FIG. 5 is a bottom plan view thereof;

FIG. 6 is a left elevational view thereof;

FIG. 7 is a right side elevational view thereof; and,

FIG. 8 is a rear elevational view thereof.

The paper roll shown in broken lines in FIG. 2 depicts environment and forms no part of the claimed design.

1 Claim, 8 Drawing Sheets
